UNITED STATES PATENT OFFICE.

ISAAC RADFORD HANSON, OF OCONEE, AND JACOB ANDREW HANSON, OF VERNON,
ILLINOIS.

RAIL-JOINT.

1,190,403.

Specification of Letters Patent.

Patented July 11, 1916.

Application filed January 21, 1916. Serial No. 73,389.

To all whom it may concern:

Be it known that we, ISAAC RADFORD HANSON and JACOB ANDREW HANSON, citizens of the United States, residing at Ocnee and 5 Vernon, respectively, in the counties of Shelby and Marion, respectively, and State of Illinois, have invented new and useful Improvements in Rail-Joints, of which the following is a specification.

10 The present invention relates to improvements in railway joints and the primary object of the invention is to improve the construction and increase the efficiency of devices of this character.

15 With the above and other objects in view, the improvement resides in the construction, combination and arrangement of parts set forth in the following specification and falling within the scope of the appended claims.

20 In the drawings: Figure 1 is a side elevation of two rails connected in accordance with the present invention, Fig. 2 is a transverse sectional view approximately on the line 2—2 of Fig. 1, Fig. 3 is a similar section approximately on the line 3—3 of Fig. 1, Fig. 4 is a horizontal section approximately on the line 4—4 of Fig. 1, Fig. 5 is a perspective view of one of the joint chair sections, and Fig. 6 is a similar view of the 25 co-acting chair section.

In the drawings 1—1 designate two rails of the ordinary construction which have their webs provided with the usual bolt openings 2.

30 The rails 1 rest upon a rail chair constructed in accordance with my invention and connected by the same, while the chair rests upon certain of the supporting ties 3.

The chair comprises two substantially 35 similar members, indicated for distinction, by the numerals 4 and 5 respectively, and the section 4 is adapted to rest upon the section 5. Each of the chair sections includes a base 6 which comprises a flat member which has its ends, which rest upon the ties 3, of a greater width than its central portion, the said central portion or what may be termed web, indicated by the numeral 7, being of a width slightly greater 45 than the width of the base flanges of the rails, while the ends 8 extend laterally from the opposite longitudinal edges of the web for any determined or desired length. Each 50 of the members 4 and 5 is interiorly formed

with a side 11 and 12 respectively. Each 55 of the sides includes a vertically straight longitudinally extending plate which is provided with inwardly extending studs 13 that are arranged to be received in the bolt openings of the respective rails 1 and each of 60 the said vertical plates is formed with an angular flanged plate 10 whereby the said sides are shaped to engage with the opposite sides of the rails. The plate 10 of the member 4 connects directly with the base 65 of said member approximately in a line with the outer edge of the web of the base of the said member, but the flanged plate 10 of the section 5 is connected at its ends by outwardly extending flat members 9 that may 70 be provided by bending the outer edges of the end members 8 of the base of the said member 5, the member 9 being arranged to overlie the said ends 8 and being spaced from the plate a distance approximately 75 equaling the thickness of the ends of the member 4. The portions 10 are provided with angularly arranged elongated openings 15—15 which register with similar openings in the portion of the ends 8 below the said 80 members 9, and the inner extensions or ends of the base 6 of the member 5 are provided with similar openings 14. The ends 8 of the members 4 are provided with elongated openings 14' which are arranged at different 85 angles from the openings 14 so that when the section 4 is arranged upon the section 5 the openings 14' thereof will be disposed at approximately a right angle with respect to the openings 14.

90 When the chair members are arranged upon the ties to engage with the rails, securing elements such as spikes 16 are passed through the openings 15, 14' and 14 of the assembled chair members, the spikes engaging with the walls provided by the openings having a wedging effect upon the chair members to force the same toward each other and as a consequence into tight engagement with the opposite sides of the rails.

100 The side members of each of the chair members are reinforced on their outer faces by angularly disposed ribs 17 and the web 7 of the chair member 5 is provided with longitudinally extending truss brace members 18 and the opposite ends or shoulders of said truss braces are disposed to contact 105 with the opposite sides of the ties 3.

Having thus described the invention, what we claim is:

1. A rail joint including two chair sections having their ends formed with lateral extensions, the said lateral extensions upon one side of one of the chair members being formed with pockets to receive the lateral extensions upon one of the sides of the other chair member, each of the chair members having one of its longitudinal edges between the lateral extensions on one side thereof provided with an inwardly extending angular flange to engage with the base flanges of the rails and the lateral extensions being likewise formed with similar flanges, said flanges terminating in vertically extending portions which are adapted to be received in the fishing spaces and to contact with the heads of the rails, the vertical portion of each of the chair members having inwardly extending lugs adjacent one of its ends, said lugs being adapted to be received in the bolt openings in the flanges of the rails, reinforcing ribs between the rail engaging members and lateral extensions of each of the chair sections, means passing through the said extensions for securing the joint chair to the rail ties, and said means permitting the lateral and longitudinal adjustment of the said sections with relation to the rails.

2. In a joint for railway rails, a chair comprising two members each including a central web upon which the rails rest, and

having their ends provided with members 35 extending laterally from the webs, the extensions upon one side of one of the chair sections being formed with pockets to receive the extensions upon one side of the other chair sections, the said extensions having registering elongated openings which are arranged at an angle to the other openings with which they align, the webs having their underfaces formed with longitudinal reinforcements and the ends of said reinforcements adapted to abut with the opposite faces of two of the ties upon which the chair is supported, the outer longitudinal edge of the web of each of the members being provided with an overlying rail engaging flange and the lateral extensions being likewise flanged, all of the flanges being formed with vertical extensions which are adapted to contact with the webs to underlie the heads of the rails, means provided upon the said vertical extensions for engaging in the bolt openings in the rails, and reinforcing ribs between the vertical extension and flanges of the lateral ends, and securing means passing through the angular 60 alining openings and entering the ties.

In testimony whereof we affix our signatures in presence of two witnesses.

ISAAC RADFORD HANSON.
JACOB ANDREW HANSON.
